FOLDABLE BOTTLE DISPLAY

Filed Nov. 22, 1939

UNITED STATES PATENT OFFICE

2,265,679

FOLDABLE BOTTLE DISPLAY

Frederick A. Sunderhauf, Rutherford, N. J., assignor to Reynolds Metals Company, Richmond, Va., a corporation of Delaware

Application November 22, 1939, Serial No. 305,612

2 Claims. (Cl. 248—174)

This invention relates to an improved collapsible or knockdown display, formed of cardboard stock or the like, preferably metal foil coated on one or more surfaces, and of the type particularly adapted for the display of bottles in an attention compelling manner; and furthermore of a type which can be easily and economically die-cut and die-scored, from a single blank of material, which may be shipped flat in quantities to the user thereof, and easily assembled to give a strong and stable display.

Heretofore, a variety of displays for bottles have been suggested but many of them have been expensive to fabricate, or have been bulky, unattractive, difficult to assemble, or have not been flat collapsible for shipping purposes: some of the prior art displays have been subject to all of said disadvantages, while others have been subjected only to certain of the same.

Therefore, it is an object of my invention to provide a bottle display of attractive design which can be economically die-cut and die-scored from a single blank of material, by modern continuous die-stamping operations, which can be shipped flat from factory to user, and which can be easily and rapidly assembled to form a strong and stable display for merchandise.

It is a further object of my invention to provide such a display with a unique easel arrangement which serves to maintain the display in upright and open position, and which also serves as a platform for a bottle, or other appropriate merchandise to be displayed.

It is a further object of my invention to provide such a display with an attractive base portion, formed of angulated outer and inner panel members, hingedly connected, and a rearwardly inclined upper portion, suitable for carrying a slogan or other advertising matter, the said upper portion being inclined at an angle of about 30° from vertical rearwardly; and to provide all of said parts connected one to another by die scorings so that the same are foldable in their desired relation from a one piece flat collapsible integral blank.

Still a further object of my invention is to provide a display, as described, which may be formed without wastage of material or cut-outs, it being my desire to save as much stock as possible.

These and various other objects and advantages will be readily understood in the following description taken in connection with the accompanying drawing of preferred embodiments of the invention, in which it is obvious that modi-

fications may be made without departing from the scope of the appended claims:

In the drawing:

Fig. 1 is a plan view of the die-cut and die-scored blank showing the relationship of the parts after die-cut and die-scoring operations are completed;

Fig. 2 is a plan view of the outer easel member;

Fig. 3 is a plan view of two platform supports;

Fig. 4 is a plan view of the assembled blank and easel, collapsed flat for shipping purposes;

Fig. 5 is a perspective view of the display in assembled position;

Fig. 6 is a section on the line 6—6 of Fig. 5;

Fig. 7 is a section taken on the line 7—7 of Fig. 6;

Fig. 8 is an enlarged fragmentary section taken on the line 8—8 of Fig. 5, showing one type of appropriate material in which the blank may be constructed, and also showing one method of die-scoring the panel members.

In these figures, a flat collapsible display 10, adapted particularly for the display of bottles, or bottled goods, is formed from a die-cut and die-scored integral blank 12, with a base or lower portion generally identified as 14, and an upper portion 16 adapted to carry advertising or the like. The blank 12 will ordinarily be formed of cardboard stock and may have mounted thereon, if desired, a sheet of reflective aluminum foil indicated as 18 in Fig. 8.

The base portion 14 of the display will ordinarily taper upwardly, as shown, and include two central hinged panels 20 yieldable rearwardly to form a forwardly open angle (see Fig. 5), and two outer or side marginal panels 22 which are hingedly connected by virtue of their two foot-like continuations 24, which are hinged at 26 to form a front lower base panel, generally identified as 28, which base panel, when the display is open to an upright position, is yieldable forwardly to form a rearwardly open angle.

Central panels 20 are defined from outer panels 22 by front score lines 30, and are separated one from another by rear score line 32. The lower portions of central panels 20 are defined from base panel 28 by a score cut 34, and score cut 34 will normally be so made to provide an attractive curved extension 36 at the central portion of base panel 28; this curved projection also tends to retain an article of merchandise, such as a bottle, upon the foldable platform member identified as 38.

The upper portion 16 of the display, which

may take an attractive rounded form, as shown, if desired, is separated from outer panels 22 by angulated score lines 40, which angulated score lines 40 intersect the score lines defined by outer limits of central panels 20 at an angle of about 120°, thereby allowing the upper portion 16 of the display, when the lower portion is in upright position, as shown in Fig. 5, to incline rearwardly at an angle of about 30°.

When covering with reflective aluminum foil, the central panel members will mirror any object placed upon platform 38, and the angulated tapering panels make an attractive and attention compelling display, particularly in conjunction with the rearwardly inclining upper panel portion 16 which may carry advertising or the like.

The flat folding platform and easel member, identified generally as 38, comprises a platform member proper 42 hingedly connected to a right angularly foldable strip member 44. The ends of strip member 44 will be glue mounted to two free ended members 46, which in turn are respectively glue mounted by one end to the bottom of the display at the rear thereof. As indicated in Fig. 4 the platform member proper 42, when the display is flat folded for shipping, extends upwardly in front of central panels 20. When the display is assembled to the form shown in Fig. 5, with the rear of strip member 44 assuming approximately a right angle form, and together with the forward portion of base panel member 28, forms approximately a square, platform member 42 may be folded downwardly to a horizontal plane which is below the upper limits of base panel 28. The two free strip members 46 are so arranged that in this position of the display they extend centrally of the display and diagonally of the rough square just described; these two free strip members 46, together with right angularly folded strip member 44, give a firm support to the platform member 42 and make the display extremely stable. It will be noted that a marginal portion 48 of platform member 42 will overlie a portion of strip member 44 to which it is not connected, as best shown in Fig. 7, thus giving platform member 42 added support. For purposes of folding the platform member 42 in a horizontal plane when the display is collapsed flat, as shown in Fig. 4, a notch will be provided in the said platform as indicated at 50 to permit the platform member to pass by the juncture of one of the central panel portions 20 and base panel 28 as indicated in Figs. 2, 5 and 7.

It will be recognized that refinements and modifications may be made in displays which embody my invention, either in whole or in part, but that the essence of my invention comprises a flat collapsible die-cut and die-scored display with a stable platform for articles of merchandise, particularly bottles, the said display being adapted to be cheaply and economically formed, so far as its main body portion is concerned, from a single die-cut and die-scored integral blank, which, when assembled, produces an attention compelling display having various angulated panels.

It will be further recognized, that while the illustrated form of the invention, which I have described, represents a preferred embodiment, I do not wish to limit myself to the details shown, since it is obvious that the same may be varied without departing from the spirit of the invention as described in the appended claims and that the display may be especially varied by changing the shape or plane of top member 16.

Having described my invention, what I now claim is:

1. A flat, foldable display including platform and easel members for supporting an article of merchandise and for maintaining the display in upright position, and a one-piece die-cut, and die-scored body member including two central hinged panels yieldable rearwardly to form a forwardly open angle, two marginal side panels attached to said central panels, said side panels provided with foot extensions hinged together along a line of fold and yieldable forwardly to form a rearwardly open angle, said foot extensions provided with centrally and integrally raised retaining walls and said marginal panels hinged at their upper ends along angulated score lines to a top panel, said score lines positioned to provide a backward tilt to said top panel.

2. A structure as provided in claim 1 wherein the easel members and platform means comprise a right angularly foldable strip member secured at its free ends to said marginal panels and adapted in display position to form a square with said foot extensions, two free ended strip members secured at one end to said foot extensions and extending diagonally into said square, and a platform member integral with said right angularly foldable strip members and adapted to fold forward and overlie said free ended strip members, thereby providing a rigid supporting platform.

FREDERICK A. SUNDERHAUF.
